UNITED STATES PATENT OFFICE.

GEORGE H. DAY, OF SOUTHBIDGE, MASSACHUSETTS, ASSIGNOR TO AMERICAN OPTICAL COMPANY, OF SOUTHBIDGE, MASSACHUSETTS, A VOLUNTARY ASSOCIATION OF MASSACHUSETTS.

OPHTHALMIC MOUNTING.

1,241,716.

Specification of Letters Patent.

Patented Oct. 2, 1917.

Application filed July 27, 1916. Serial No. 111,591.

To all whom it may concern:

Be it known that I, GEORGE H. DAY, a citizen of the United States, residing at Southbridge, in the county of Worcester and State of Massachusetts, have invented certain new and useful Improvements in Ophthalmic Mountings, of which the following is a specification.

This invention relates to improvements in ophthalmic mountings and has particular reference to a novel construction of combined metallic and non-metallic materials.

One of the leading objects of the present invention is the provision of novel and improved means for readily connecting a mounting composed of metallic and non-metallic members to present a neat and attractive appearance and facilitate assembling or separation of the parts as desired.

20 A further object of the invention is the provision of an improved construction of this nature constructed to particularly facilitate the insertion or removal of the lenses without the necessity of undue stretching or 25 distortion of the non-metallic portion of the frame.

30 A further object of the invention is the combination of the metallic and non-metallic parts in such manner that the non-metallic portion of the frames shall have a metallic brace throughout which shall be invisible when viewed from the front of the mounting, yet which shall securely retain the parts and shall be visible from the side 35 or rear of the mounting so that a person examining the frame may readily determine the character of the same.

40 Other objects and advantages of my improved construction should be readily apparent by reference to the following specification taken in connection with the accompanying drawings forming a part thereof, and it will be understood that I may make any modifications in the specific details of 45 construction shown and described within the scope of the appended claims without departing from or exceeding the spirit of the invention.

50 Figure I represents a front view of one form of mounting constructed in accordance with and embodying the generic principles of my invention.

Fig. II represents a sectional view taken as on the line 2-2 of Fig. I.

Fig. III represents a rear view of the 5 composition or non-metallic portion of the frame, and

Fig. IV represents an edge view of said member.

In the drawings, the numeral 1 designates the usual eyeglass bridge which may be formed of suitable material and has secured to each end thereof the eye wire or rim 2, split at its outer portion and bearing the end piece sections 3 serving to unite the rim in the usual manner and form points of attachment for the temples 4 designed to retain the mounting in position on the face.

Inclosed within said rim is my improved composition or non-metallic lens frame member comprising a wire ring having the rounded portion 5 and the reduced preferably V-shaped portion 6 of less exterior diameter than the diameter of the portion 5. The purpose of this should be readily apparent by reference to the drawings from which it will be seen that the shape of the portion 6 is such as to just fit within the inner grooved face 7 of the rim 2 while the diameter of the outer portion 5 is such that it projects outwardly beyond the outer face of the rim 2 and consequently conceals this rim when the mounting is viewed from the front.

The composition member as an entirety is 85 formed with the inner groove 8 adapted to receive a bevel edged lens 9, while to facilitate insertion of the lens within this frame, and to provide of its secure gripping and retention in position when inserted, I have 90 formed in the portion 6 the slot or slots 10 extending just through the portion 6 but not through the portion 5.

The advantages of this construction should be at once apparent by reference to the 95 drawings from which it will be understood that on account of the formation of these slots the portion 2 may be readily opened up as by extending at the portion 5 or slight springing of the portion 2 itself to 100 facilitate the ready insertion of the lens in the groove 8 while after the lens has been inserted the parts will automatically spring back into position to retain the lens, while as the frame 2 is placed in position and the end pieces 3 tightened together in the usual manner as by a suitable securing screw, the tightening of the rim or band 2 will tend

to draw together the split portion 6 embraced thereby to tightly clamp and lock this portion in engagement with the lens, the tightening of the band thus serving both to lock the lens in position within the non-metallic member and to secure the non-metallic member in position within the rim.

While I have shown my improved construction as mounted within an encircling frame or the like, it will be understood that the composition member described may be employed without a frame as with a rimless mounting, or with other suitable construction and will, in this form, prove equally efficient and satisfactory in retaining a lens in position.

I claim:

1. A non-metallic lens securing frame for an ophthalmic mounting comprising an interiorly grooved annulus having a continu-

ous ring at one side and a split ring at the opposite side thereof, whereby the split portion may be sprung to facilitate the insertion of a lens into the interior groove of the device.

25

2. In an ophthalmic mounting, the combination with a lens retaining device having a continuous annular portion at one side thereof and a slotted portion at the opposite side thereof, said annulus having a central lens receiving groove, of a rim member embracing the slotted portion to clamp the parts together and secure a lens in position therein.

30

In testimony whereof I affix my signature in the presence of two witnesses.

GEORGE H. DAY.

Witnesses:

EDITH M. HALVORSEN,
ESTHER M. LAFLER.
